United States Patent

Des. 235,319
Patented June 10, 1975

235,319

OPTICAL BUILDERS' LEVEL OR THE LIKE

J. Peter E. Kooi, Succasunna, N.J., assignor to Keuffel & Esser Company, Morristown, N.J.

Filed Aug. 10, 1973, Ser. No. 387,562

Term of patent 14 years

Int. Cl. D10—04

U.S. Cl. D10—66

FIG. 1

FIG. 2

FIG. 3

FIG. 4

FIG. 1 is a left side elevational view of an optical builders' level embodying my new design;

FIG. 2 is a rear elevational view thereof;

FIG. 3 is a top plan view thereof;

FIG. 4 is a right side elevational view thereof; and

FIG. 5 is a front elevational view thereof.

I claim:

The ornamental design for an optical builders' level or the like, as shown and described.

UNITED STATES PATENT OFFICE
CERTIFICATE OF CORRECTION

PATENT NO. : Des. 235,319

DATED : June 10, 1975

INVENTOR(S) : J. Peter E. Kooi

It is certified that error appears in the above-identified patent and that said Letters Patent are hereby corrected as shown below:

In the line naming the Inventor(s), after "Succasunna," insert --and Allister L. Baker, Denville,--

In the same line, change "assignor" to --assignors--

In the specification, change "my" to read --our--, and change "I claim" to read --We claim--

Signed and Sealed this

Second Day of May 1978
